EDWARD JACOB DEISLEY, OF PHILADELPHIA, PENNSYLVANIA, ASSIGNOR TO EDWARD G. BUDD MANUFACTURING CO., OF PHILADELPHIA, PENNSYLVANIA, A CORPORATION OF PENNSYLVANIA

DOOR-WINDOW FRAME

Application filed January 29, 1925. Serial No. 5,429.

My invention relates to pressed metal window frames of the type commonly found in closed body vehicles but it is not improbable that other adaptations may be found for it.

More specifically, it relates to those constructions in which it is sought to reduce to a minimum the opaque projections of the window frames as taken from the interior of the car. There has been of recent months a great forward movement in the art of body building having as its principal aim the marked increase of the range of vision from within the car whereby the comfort of passengers and their safety is greatly enhanced. This movement has resulted in the employment of very thin pressed metal sections in window frames particularly in door window frames where the triple considerations imposed by window mounting, door frame and door posts are more liable to multiply the area of opaque projection than in cases where window frames alone are involved. In one type of car with which I am most familiar, this endeavor has resulted in a window or door frame the main body section member of which is of Z form. The main web is disposed transversely, the glass run channel is formed upon it, and the arms of the Z section are respectively constituted the outer of them the outer door jamb overlap upon the body frame members, and the inner of them the means of securing the inner paneling or upholstery, and one side wall of the glass run channel. These rails as well as other forms of rails with which I am familiar have required the employment of metal of a substantial gauge in order to give them the requisite stiffness without increasing the area of opaque projection.

It is the principal aim of my invention to give such greater strength without increasing the gauge of the metal and without increasing the area of opaque projection. I attain this object by employing a subordinate reinforcing section member of a depth not exceeding the depth of the glass run channel. The depth of this glass run channel is commonly determined by the length of the inner arm of the Z-section. So much depth is necessary in order to properly align the

glass I have conceived therefore that I may construct the window rail of a compound section the total depth of which does not exceed the depth of the window glass run channel without increasing the opaque projection.

In the embodiment of my invention which I illustrate herein I have attained this principally by applying mouth down to the main web of the Z-section of the window rail a channel, preferably in the form of a unitary panel stamping and of a depth not exceeding that of the glass run channel. Moreover, I have simplified the structure while so strengthening it by constituting the inner side wall of the channel the outer side wall of the window glass run, eliminating the necessity for the provision of special angle members for that purpose. Still further, in the exposed exterior of the window glass frame, I have changed the configuration of the reinforcing channel of the new compound section to give it a finished bead-like appearance thereby markedly improving the general appearance of the window frame at large.

In the drawings:

Fig. 1 is a side elevation of a door frame having a window in its upper portion taken from the interior.

Figs. 2 to 6 are respectively cross-sections on lines of corresponding numbers appearing in Fig. 1 and in the direction of applied arrows.

Figs. 7 to 9 are similar cross sections of a modified form, taken on lines corresponding to those of Figs. 4 to 6.

Throughout the drawings, the main section member of Z cross-section has its main body identified by the numeral 10, its outer arm designated 11, and its inner arm designated 12; while the reinforcing subordinate section member of channel form has the bottom of its channel designated 13, its inner side wall designated 14 and its outer side wall designated 15. It will be quite apparent that the side and top rails are of compound section throughout their upper portions, being formed in each case by the principal section member and the subordinate or reinforcing section member. The lower portions, however, are of the usual sections shown in Figs. 100

2 and 3, a section of greater height than that of the upper portions.

The outer arm 11 of the main section member of Z form constitutes in each case the 5 perimetral overlap of the frame across the door jamb. Throughout the frame also the transversely extending main body 10 of the Z section constitutes the transverse main body web of the pressed metal rail. Similarly, 10 the inner arm 12 of this main section member constitutes in the upper reaches the inner side wall of a glass run channel 16. In the lower reaches it constitutes a means of securing the inner panel (of which the lockboard 15 panel 17 is an example) to the inner face of the door frame and a support too for the upholstery (not shown). The length of arm 12 is primarily adjusted in the upper reaches of the rail surrounding the window opening 17 20 to the practical depth of the window glass channel 16, this depth being that minimum value consistent with efficient guiding of the glass whereby the opaque projection is cut down to a minimum.

25 The channel section subordinate section member 13, 14, 15, is attached mouth down to the plane inner face of the plane form main body web 10 of the Z section in the upper reaches. In the form shown in Figs. 7 to 9, 30 member 13, 14, 15 is of a width less than the total height of the plane main body web 10 of the Z section, less by an amount substantially equal to the width of the glass run channel 16. Its side wall 14 adjacent to the 35 inner arm 12 of the Z section forms with the arm 12 the glass run channel 16. This arm is provided with an inwardly extended side wall flange 18 by means of which the channel section reinforcing member is spot welded 40 to the plane face of the web 10. This flange 18 is of such width that it spaces the side wall 14 the proper distance from the arm 12 to give the glass run channel its proper width. In this function, it acts as a spacing member 45 in the welding assembly. The opposite side wall 15 is substantially in line with the outer jamb overlap arms 11 of the main Z section, is extended laterally to outwardly overlap these arms and then inwardly around the outer 50 ends of the arms as at 19 where they are welded thereto, preferably by arc-welding on the inside to the arms 11 thereby avoiding any danger of marring the exterior as would be occasioned if spot welding were used 55 through the three thicknesses.

At the top rail (see Fig. 9) the main Z section 10, 11, 12 is of less height than the corresponding sections of the body rails, the height of which in the embodiment shown is 60 substantially uniform. The window glass run 16 is here formed by a supplementary header member 20 of angle cross section having one branch 21 removably secured to the main body web 10 of the header rail and the other branch 22 depending substantially par-

allel with the inner arm 12 of the Z section and spaced a sufficient distance therefrom to give the proper glass run channel width to channel 16. The reinforcing channel member in this case has its side walls 14, 15 respectively extended to outwardly overlie the respective arms 12, 11 of the main section of Z form. The inner side wall 14 is spot welded to the inner arm 12, while the outer extended arm 15 is turned around the outer overlap flange 11 as at 19 and arc-welded to the inner face of the arm as in the other instance.

In the form shown in Figs. 4 to 6 reinforcing channel section member 13, 14, 15, 70 is of reduced width. The side wall 15 is moved inwardly in this reduction of channel width. In these upper portions it is extended first laterally parallel and contiguous to the plane form main body web 10 of the main section of Z form, then outwardly and inwardly as at 19 around the outer overlap arm 17. Moreover, the bottom wall 13 and the side wall 15 are merged into each other to the substantial elimination 80 of the angle between them with the result that the section in these upper lengths of the rails is given exteriorly a bead-like appearance, the bottom wall 13 and the side wall 15 having an exteriorly convex form. The 85 construction at the top rail is similar as clearly shown in Fig. 6.

In each case, I have retained a depth of channel section in the subordinate reinforcing member 13, 14, 15 not exceeding the 90 depth of the glass run channel 16. The total body cross-section of the door, therefore, excluding the outer overlap flange is of a depth not substantially exceeding the required 95 depth of section of the glass run channel. The opaque projection cannot possibly be increased therefore by such means. On the 100 other hand, however, the strength of the frame for a given weight is very greatly increased, for especially in the sections 105 shown in Figs. 7 to 9, the combined section of the main body 10 of the principal section and the channel of the reinforcing section is of box form, of very much greater thickness 110 than the thickness of gauge of either of the 115 pressed metal section members which form it. As is well known, the box section gives a very great strength for a given weight. The combined section in the form of Figs. 4 to 6 is likewise of box form, though in this 120 case it is of reduced area and approaches a triangular shape in lieu of a rectangular shape. While the strength of the triangular section of reduced area is somewhat less than that of the rectangular section, yet I am able 125 to achieve a very substantial gain in strength and reduction in weight by reason of the construction. This is augmented by the extended side wall 15 and its extensive overlap with the outer door overlap flange 11. 130

Moreover, by reason of the fact that the bottom and side walls 13 and 15 are merged into each other and the outer angle eliminated, the range of vision defined by line 23 tangent to the bottom 13 and the juncture of the main body 10 and outer arm 11 indicated by line 23, a range possible with earlier types of thinner and weaker sections, is fully retained.

10 And withal, the exterior contour lines and general appearance are rendered very attractive, in many cases substantially improved, by reason jointly of the attractive section afforded by merger in various ways 15 of the bottom 13 and side wall 15 of the reinforcing channels, presenting the bead-like appearance, and by reason of the fine exterior finish afforded by the sheathing of the rather heavier and coarser main section 20 10, by the outer and overlap extension 19 of the reinforcing section member. Light gauged material with inferior surfacing may be used with economy in the main section members 10, 11, 12, while thin gauge 25 metal of highly finished and fine grained surface may be used for the subordinate and reinforcing section members 13, 14, 15. The markedly increased strength, the unimpaired vision, and the fine contour lines and 30 superior exterior finish are actually obtained with substantial economy of metal due jointly to a retention of the actual weight of metal at a minimum value and the use of a cheaper metal, less expensive to fabricate 35 for the major portion of that weight.

Though my invention is simple, it has such substantial merit in its own field that ingenuity will without doubt be directed to circumvent it. This cannot but result in 40 quite a number of solutions which are generically the same as my own invention. These the annexed claims should cover as fully as they cover the embodiment herein shown.

What I claim is:

- 45 1. A top rail for doors of closed vehicle bodies comprising a main member having a transverse portion of web cross section, flanged at its outer and inner edges, and a panel stamping of hollow form having one side open applied with its open side to the inner face of the main member and secured at its opposite edges to the flanges of said main member.
- 50 2. In a door, the combination with spaced pillars and a cross bar, of a panel secured to said pillars and having a finish strip at its upper end partially enclosing said cross bar, and a header secured to said cross bar and finish strip and cooperating with said finish strip to conceal said cross bar.
- 55 3. A top rail for doors of closed vehicle bodies comprising a main member of web cross section of simple Z-form, and a panel stamping of hollow form having one side open applied with its open side to the inner

face of the main member and secured at its opposite edges to the oppositely extending arms of the Z.

In testimony whereof I hereunto affix my signature.
